G. C. Kennedy,
Attorney.

UNITED STATES PATENT OFFICE.

WILLIAM F. CLOSE, OF WATERLOO, IOWA.

HOLDER FOR LIQUID-CONTAINERS.

1,339,163.

Specification of Letters Patent.

Patented May 4, 1920.

Application filed January 9, 1919. Serial No. 270,358.

To all whom it may concern:

Be it known that I, WILLIAM F. CLOSE, a citizen of the United States of America, and a resident of Waterloo, Blackhawk county, Iowa, have invented certain new and useful Improvements in Holders for Liquid-Containers, of which the following is a specification.

My invention relates to improvements in 10 holders for liquid containers, and the object of my improvement is to furnish for liquid containing vessels, and particularly for reservoirs having special delivery devices, a holding device, which will be formed for 15 adjustment in mounting it upon projections of varying widths, and which will also have supporting and clasping means for receiving and holding such a reservoir removably.

This object I have accomplished by the 20 means which are hereinafter described and claimed, and which are illustrated in the accompanying drawings, wherein Figure 1 is an elevation of my improved device, with parts broken away, and Fig. 2 is a perspective view of the suspension hanger for the 25 reservoir thereof.

Similar numerals of reference denote corresponding parts throughout the several views.

30 The reservoir for liquids of my device may be a common fruit-jar 1 having the usual screw-cap 2, or may be of any other desirable form. The reservoir-cap 2 is supplied with an air-port tube 3 for entrance of air, 35 preventing the formation of a vacuum in the reservoir.

An orifice 4 is supplied in the bottom of said reservoir to permit the passage of the threaded end 7 of a tubular part of a valve-chamber 8, the latter having a rock-valve 40 therein actuated manually by the usual external finger-piece, and said valve-chamber has a vent-tube or terminally thickened nipple 9 to removably receive thereover an end 45 of an elastic tube 10 which has on its other end a terminal syringe nipple 11.

The threaded tube 7 is secured and sealed to the bottom of said reservoir by the internal and external nuts 5 and 6, respectively.

50 The device thus described is a complete fountain syringe, with its fluid delivery controlled by the valve in the chamber 8, and

the reservoir may be filled by mere removal of the screw-cap 2.

I have shown, however, convenient means 55 for detachably adjustably supporting or hanging said reservoir 1 on supports of varying widths. This consists of a resilient flat split-ring 12, preferably outwardly flanged along its upper edge to insure sufficient stiffness, to inclose and yieldingly resiliently grip the lower part of said reservoir 1. This split-ring may be suspended from a wall or other support on a nail or other projection by the following described 60 hanger, or any mechanical equivalent thereof.

The numeral 13 denotes a rod bent and formed into a closed loop, of which the upper part comprising the like downwardly 70 divergent or A-shaped limbs 13 is used to hang upon any suitable projection, the A-shape permitting hanging on projections of different widths, and insuring firm frictional contact therewith due to the weight of 75 the suspended bodies.

Said rod is bent forwardly at 14 toward the split-ring 12, then bent downwardly at 15 to contact with the ring vertically, then bent under the ring 12, forming the closed 80 semi-circular part 16 which crosses and underlies the bottom of the reservoir 1 and supports same. The rod parts 15 may be secured to the split-ring 12 by any desired means, such as by soldering. 85

The reservoir 1 is easily and quickly placed in or removed from the split-ring 12 and the supporting rod-part 16, the interspace between the split-ring ends permitting passage therebetween of the parts of the 90 delivery-device suspended below said reservoir. Since the bottom of the reservoir is slightly domed, any sedimental matters in the liquid contents of the reservoir will settle in the lower part of the reservoir, to not 95 pass away through the syringe, but may be removed from the reservoir before refilling. The air-tube 3 prevents vacuum in the reservoir, insuring free delivery.

Having described my invention, what I 100 claim as new, and desire to secure by Letters Patent, is:

Holding-means for liquid containers, comprising a rod bent and having its ends

united to form an inverted V-shape hanger adaptable to receive varying widths of projecting supports between its divergent members, the lower parts thereof being offset, 5 a resilient split-ring fixedly mounted on the offset parts, and the lower parts of the said offset parts being bent into a closed loop

crossing and underlying the bottom of said split-ring to support a container removably clasped by the split-ring.

Signed at Waterloo, Iowa, this 23rd day of December, 1918.

WILLIAM F. CLOSE.
